UNITED STATES PATENT OFFICE.

WILLIAM C. SANDLIN, OF ANDREWS, NORTH CAROLINA, ASSIGNOR OF ONE-THIRD TO ARTHUR MOULTON AND ONE-THIRD TO C. W. SAVAGE.

INSULATOR.

No. 891,955.

Specification of Letters Patent. Patented June 30, 1908.

Application filed September 25, 1905, Serial No. 279,989. Renewed December 16, 1907. Serial No. 406,768.

To all whom it may concern:

Be it known that I, WILLIAM C. SANDLIN, a citizen of the United States, residing at Andrews, in the county of Cherokee and State of North Carolina, have invented certain new and useful Improvements in Insulators; and I do declare the following to be a full, clear, and exact description of the invention, such as will enable others skilled in the art to which it appertains to make and use the same.

This invention relates to insulators for telegraph, telephone and electric power wires, and one of the principal objects of the same is to provide an insulator which will not require fasteners for the line wire to the insulator, and which will be economical in that it will save labor and time in the insulation of telegraph and telephone lines.

Another object is to provide an insulator which will hold the line wires so as to prevent sagging in case of breakage between two poles.

These and other objects, which will appear as the nature of the invention is better understood, are accomplished by means of the construction illustrated in the accompanying drawings in which—

Figure 1 is a side view of an insulator made in accordance with my invention; Fig. 2 is a plan view of the same, and showing a short section of the line wire secured thereto; and Fig. 3 is a sectional view through the cross arm of a telegraph pole, and showing the manner of connecting my insulator to said cross arm.

Referring to the drawings for a more particular description of my invention, the numeral 1 designates the base of my insulator, which, as shown, is preferably rectangular in plan, and provided with an undercut or dovetail recess extending lengthwise from end to end of the base. Projecting upwardly from the base 1 are two knobs, each comprising a head 2 and the groove or neck 3 intermediate the head and base of the insulator. The two insulator knobs or heads are disposed at such

distances apart as to provide just sufficient space between them to readily permit the passage of the line wire 4, said line wire passing around within one of the grooves 3 between the two heads and around the opposite side of the groove in the other knob, as shown in Fig. 2 of the drawings. This can be quickly done in attaching the line wire to the insulator, and will insure a safe connection between the wire and insulator. Should the wire break between the poles, the tendency to sag along the entire line would be prevented by the bend in the wire around the two insulators, when added to the weight of the severed wire between the two poles. The cross arm 5 is connected to the base of the insulator by means of the dovetail 6, as illustrated in Fig. 3, and, if found desirable, a nail or other similar fastening may be driven at the opposite ends of the insulator base, to hold the same in place upon the cross arm. It is noted that the two heads of the insulator are disposed in a line at right angles to the direction in which the line wire extends.

Having thus described my invention, what I claim as new and desire to secure by Letters-Patent is:

In a device of the class described and in combination with a supporting cross arm having a dove-tailed tongue, a one-piece insulator comprising a base having in its lower face a dove-tailed groove formed to receive said tongue and serve through interlocking engagement therewith as the sole means for attaching the insulator to the cross arm, said base being provided on its upper face with a pair of marginally grooved knobs arranged on the medial line of the base and parallel with the longitudinal axial line of the cross arm.

In testimony whereof I have hereunto set my hand in presence of two subscribing witnesses.

WILLIAM C. SANDLIN.
